UNITED STATES PATENT OFFICE

JOHN J. CONEYS, OF PHILADELPHIA, PENNSYLVANIA.

EXPLOSIVE SHELL.

SPECIFICATION forming part of Letters Patent No. 644,896, dated March 6, 1900.

Application filed May 9, 1898. Renewed January 19, 1900. Serial No. 2,070. (No model.)

To all whom it may concern:

Be it known that I, JOHN J. CONEYS, a citizen of the United States, residing at Philadelphia, in the county of Philadelphia and State of Pennsylvania, have invented a certain new and useful Improvement in Explosive Shells, of which the following is a specification.

My invention relates to a new and useful improvement in explosive shells for cannons and the like, and has for one object to so construct a shell of this description that by attaching an electric conductor thereto it may be exploded at a given time after it has left the cannon, and when this is properly indicated relative to the speed of the projectile the latter may be exploded at a given distance from the cannon, thus causing it to expend its force upon the object desired.

A further object of my invention is to provide loose wires which will swing in all directions after the shell has exploded and be made electrically alive by the conductor, with a sufficient strength of current to kill persons and animals coming in contact therewith and to set on fire vessels or buildings with which they come in contact.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a section of a shell made in accordance with my improvement before the same has been exploded; Fig. 2, a similar view showing the shell after explosion, but prior to the cap having broken loose from the wires; Fig. 3, a view showing the butt of the shell, with the wires swinging loose; and Fig. 4, a cross-section showing the stay-rods.

In carrying out my invention as here embodied, A represents the butt of the shell, and B the cap thereof, in between which is interposed a cylindrical casing or body C, thus making a receptacle for the explosive material, (indicated at D,) with which may be mixed scrap-iron or the like for effectiveness

when the shell is exploded. The three parts of the shell, as just described, are held together by the stay-rods E, here shown as six in number, one end of each rod being secured in the butt, while the opposite end passes through one of the holes F in the cap and is held in place by the pins G.

H is an eye formed with or secured to the butt of the shell, and to this eye is attached a cable I, along which run the conductor-wires J and J', the former being positive and the latter negative. The wire J is insulated from the butt of the shell, while the wire J' is attached directly thereto, and the former in passing into the explosive material is formed into a resistance-coil and is preferably of some fusible material, so that when the current is passed over this conductor it will burn out at this point and in so doing will ignite the explosive material, with the result that the body of the shell will be shattered while the cap is blown off. A series of wires K are coiled about the stay-rods E and are attached to the cap, as clearly shown at L, so that when the latter is blown off these wires will be drawn out until reaching their limit, when the cap will break loose therefrom and leave said wires free to swing to and fro, as shown in Fig. 3.

From this description the operation of my improvement will be obviously as follows: A sufficient length of cable is laid in a coil in front of the gun, one end being attached to the shell and the other fastened to a ring, so as to form a connection with the brake or switch, so that said cable may be drawn forth as the shell is projected, and when this shell is projected from a cannon it is only necessary to know the speed at which it is traveling to determine the distance from the cannon at which it is to be exploded, which latter is accomplished by any convenient switch mechanism—as, for instance, that shown in Fig. 1 at a—and when the circuit is closed by such a switch an electric current will be passed along the conductors, which will explode the shell, as before described, and when the wires K are severed from the cap this current will make these wires alive, and when any of them come in contact with a person or an animal the current will pass from the wires with sufficient energy to kill, or should

the wires come in contact with inflammable material, such as woodwork or the like, the latter will be set on fire. By this form of shell when a vessel or other object is located 5 and its distance known or calculated the shell may be projected and exploded immediately on said vessel or object, and thereby great damage effected.

The shell could be worked to great advantage by the coast-guards, and should a ship 10 come in range the shell might be exploded thereover, so that its wires spring out like arms, one resting upon the ship and the other in the water, thus forming a circuit and transmitting to the ship an enormous supply of 15 electricity, which would completely destroy all life aboard of said ship, as well as explode ammunition carried thereon.

Having thus fully described my invention, 20 what I claim as new and useful is—

The herein-described combination of a butt, a cap and a casing for forming a complete shell, stay-rods securely attached to the butt and passing through the cap, wires coiled around said stay-rods and securely attached 25 to the butt, their opposite ends being loosely attached to the cap, a cable attached to the butt adapted to be coiled upon a reel, conductors carried by the cable and so connected with the shell as to explode the contents when 30 a current is passed therethrough and leave the wires alive, as and for the purpose set forth.

In testimony whereof I have hereunto affixed my signature in the presence of two sub- 35 scribing witnesses.

JOHN J. CONEYS.
